(57) **CLAIM**

The ornamental design for a remote control unit, as shown and described.

DESCRIPTION

FIG. 1 is a perspective view of the remote control unit of this invention.

FIG. 2 is a plan view of the front of the remote control unit of the invention shown in FIG. 1.

FIG. 3 is an elevational view from the top of the remote control unit of the invention shown in FIG. 1.

FIG. 4 is a plan view of the back of the remote control unit of the invention shown in FIG. 1.

FIG. 5 is an elevational view from the bottom of the remote control unit of the invention shown in FIG. 1.

FIG. 6 is a left side elevational view of the remote control unit of the invention shown in FIG. 1; and,

FIG. 7 is a right side elevational view of the remote control unit of the invention shown in FIG. 1.
